ATTORNEYS

UNITED STATES PATENT OFFICE.

THEODORE R. MCSPADDEN, OF NOWATA, OKLAHOMA.

SUCTION-ROD-GUIDE CLAMP FOR OIL PUMPS.

Application filed January 13, 1923. Serial No. 612,533.

To all whom it may concern:

Be it known that I, THEODORE R. MCSPADDEN, a citizen of the United States, and a resident of Nowata, in the county of Nowata and State of Oklahoma, have invented certain new and useful Improvements in Suction-Rod-Guide Clamps for Oil Pumps, of which the following is a specification.

10 My present invention relates generally to a suction rod guide and outlet T protectors for oil pumping apparatus, and more particularly to a device which is utilized for the above purposes during removal of the 15 pump head for repair or substitution of parts and the reinsertion of the pump head and sucker rods, my primary object being the provision of a device which may be readily clamped in connection with an outlet T, in order to protect the internal threads of the latter and guide the sucker rod sections, so as to avoid in part the delays and therefore the expense of pump head repairs under the present operation.

In the accompanying drawing which illustrates my invention and forms a part of this specification,

Figure 1 is a side view, partly broken away and in section, showing a casing head and adjacent parts of conventional oil pumping apparatus including the outlet T.

Figure 2 is a view of substantially the same parts, with my invention in place, and

Figure 3 is a detail perspective view of 35 my improved sucker rod guide and outlet T protector detached and in open position.

Referring now to these figures and particularly to Figure 1 I have shown certain portions of a conventional apparatus for 40 pumping oil from an oil well, including the usual casing 10 having at its upper end the usual casing head, 11, downwardly through which the pump tube 12 extends, the latter housing the sucker rod 13, in sections as usual, the sections being connected by unions and the upper end of the suction rod, when in place being connected by a similar union shown at 14 with the lower end of the polish rod 15. At the upper end 45 of the pump tube 12, above the casing head 11 is a T 16 which threads on the pump tube and connects with a lateral or outlet pipe 17, the polish rod 15 working through a stuffing box 18 which is threaded at its lower end 50 into the upper end of the T 16.

As is well known at present, whenever it

is necessary to withdraw the pump head secured to the lower end of the sucker rod, for various purposes including the replacement of leathers, the stuffing box 18 is unscrewed from the T 16 and by means of a superlifting apparatus, upward pull is exerted on the polish rod 15 until union 14, connecting its lower end with the upper end of the sucker rod, is substantially above the T 16. What is known as an elevator is then clamped to the upper portion of the sucker rod 13 below the union 14 and rests upon the T 16 so as to support the weight of the sucker rod while the union 14 is detached. 60 A short section of tubing commonly known as a nipple is then slipped onto the lower end of the polish rod 15, this nipple having threads on its lower end, and the polish rod is again attached to the upper end of the sucker rod 13 after which the polish rod is again connected to the lifting apparatus so that the latter supports the weight of the sucker rod and the elevator previously referred to is removed. The nipple is then 70 shifted downwardly around the sucker rod and threaded into the upper end of the T 16, after which the elevator is again placed in position, this time resting on the nipple, and polish rod detached. 75 The various sections of the sucker rod are then lifted and successively detached in a like manner.

According to my invention a clamp 19 is proposed, of generally cylindrical form, 80 having two semi-cylindrical sections 20 and 21 provided upon their inner surfaces and intermediate their upper and lower edges with grooves 22 coacting to form an annular channel for the reception of the upper flange 95 16^a of the T 16. These sections 20 and 21 of the clamp are also provided immediately above their grooves 22 with inwardly projecting ribs 23, projecting inwardly beyond the inner surfaces of the sections below the 100 grooves and thus adapted when clamped around the upper end of the T 16, to extend inwardly beyond the inner surface of the T, as shown in Figure 2, to an extent sufficient to protect the upper threads 16^b of the T 105 and form a guide for the sucker rod 13 as the latter is lifted out of or inserted into the pump tube 12.

Above each guide rib 23, the sections 20 and 21 of my improved guide and protector 110 clamp have beveled portions 24, and these sections at one end are joined by a hinged

connection 25 and have vertically spaced exteriorly projecting ears 26 and 27 at their opposite ends.

A connecting bolt 28 is pivotally connected 5 at one end to the section 20 of the clamp by virtue of the passage of a vertical pin 29 through the ears 26 and the said end of the connecting bolt 28, and the opposite end of this bolt is threaded and adapted to be shifted 10 between the ears 26 of the section 21 so as to receive a clamping nut 30 which serves to securely clamp the sections 20 and 21 together and around the upper end of the T 16 in the position shown in Figure 2, it being noted that the lower portion of the 15 clamp section 21 has its lower edge recessed in order to fit around the side outlet of the T 16.

It is thus obvious that the clamp provided 20 by my invention may be readily connected to and disconnected from the T 16 without requiring removal and reconnection of the polish rod 15 to the sucker rod as is required in connection with the ordinary T protecting nipple and it is also obvious that my improved clamp will, when in place as shown 25 in Figure 2, effectively guide the sucker rod during removal and reinsertion of the latter in order to protect the upper threads of the 30 T 16.

In removing the sucker rod with my invention in use, the polish rod 15 is after disconnection of the stuffing box 18 from the T 16, raised until the union 14 is substantially 35 above the T 16. My improved clamp is then securely fastened around the upper portion of the T 16 as shown in Figure 2 and then the sucker rod is lifted and disjointed in the usual step by step operation.

40 I claim:

1. As an article of manufacture, a two-part clamp for the upper end of an oil out-

let T, having means to immovably engage the said outlet T and having an internal annular portion adapted to overlie the upper 45 end of the T and to extend inwardly beyond the inner surface of the T in order to protect the latter during withdrawal and reinsertion of a sucker rod through the T.

2. As an article of manufacture, a sucker 50 rod guide and T protector, consisting of a two-part clamp having means to securely join its parts and having an internal annular groove intermediate its ends and an internal annular rib above said groove. 55

3. As an article of manufacture, a sucker rod guide and T protector including a two-part clamp for engagement with the upper portion of an oil outlet T, said clamp having a hinged connection between its parts 60 at one end and clamping means adapted to connect the parts at their opposite ends, said clamp having an internal annular groove to receive the upper flange of a T and having an internal annular rib above its groove 65 whose inner surface is adapted to extend inwardly beyond the inner surface of a T to which the clamp is applied.

4. As an article of manufacture, a sucker rod guide and T protector including a two-part clamp for engagement with the upper portion of an oil outlet T, said clamp having a hinged connection between its parts at 70 one end and clamping means adapted to connect the parts at their opposite ends, 75 said clamp having an internal annular groove to receive the upper flange of a T and having an internal annular rib above its groove whose inner surface is adapted to extend inwardly beyond the inner surface of a T to which the clamp is applied, and said clamp also having an internal tapering surface above the rib, as described.

THEODORE R. McSPADDEN.
